SOUND-BOX.

1,377,632.

Specification of Letters Patent. Patented May 10, 1921.

Application filed April 17, 1918. Serial No. 229,129.

To all whom it may concern:

Be it known that I, JOHN J. SCULLY, a citizen of the United States of America, and a resident of Bridgeport, Connecticut, have 5 invented a new and useful Improvement in Sound-Boxes, which invention is fully set forth in the following specification.

This invention relates to sound-boxes and particularly to the manner of constructing 10 and assembling the diaphragm container or head and the manner of securing the diaphragm therein, and has particular utility when applied to sound-boxes of the perpendicularly-undulating-record type.

15 When a sound-box of the perpendicularly-undulating-record type is used for recording, it should bear upon the tablet with a comparatively light pressure and yet it must be sufficiently strong and rigid to be durable. 20 An object of this invention is to provide a sound-box of this type which is both extremely light and also strong and durable.

The diaphragm of the sound-box should be clamped in position with substantially 25 uniform tension so as not to produce local stresses. Commercial diaphragms do not possess mathematically plane faces nor mathematically parallel faces, nor is the material thereof absolutely homogeneous. Furthermore, 30 the gaskets employed are not mathematically exact nor absolutely homogeneous, nor are the clamping surfaces of the body member or the clamping ring true mathematical planes nor absolutely parallel. 35 Therefore, in structures heretofore employed, the setting up of local stresses has been inevitable. An object of this invention is to provide a sound-box wherein the diaphragm is clamped in position with substantially 40 uniform tension so as to avoid such local stresses.

Other objects relate to the provision of a sound-box that is simple in construction, inexpensive to manufacture, and which, while 45 both light and durable, is equally satisfactory for the reproduction and the recordation of sound.

Stated broadly, one feature of the invention is the provision of a sound-box comprising a body-member of sheet-material, preferably aluminum, and a tube of similar material, the two being secured together by tongues on the tube received in slots in the

body-member and bent over into clamping relation therewith. 55

Another feature of the invention is the provision of a sound-box having a body-member, a diaphragm, and means for clamping the margin of the diaphragm in position comprising a plurality of independent 60 clamping devices, said clamping means being preferably made of sheet-material and provided with a plurality of fingers which may be bent over into independent clamping relation with said body-member. 65

The invention is capable of receiving a variety of mechanical expressions one of which is shown on the accompanying drawing, but it is to be expressly understood that the drawing is for purposes of illustration 70 only and is not to be construed as a definition of the limits of the invention, reference being had to the appended claims for that purpose.

In said drawing—

75 Figure 1 is a perspective top view of a sound-box constructed in accordance with this invention;

Fig. 2 is a longitudinal section, the thickness of the parts being considerably ex- 80 aggerated for the sake of clearness.

In said drawing, 1 represents a tube preferably drawn from sheet-metal such as aluminum and curving at the end to provide a short elbow 2, and shown as provided at the 85 extremity thereof with a plurality of tongues 3. The body of the sound-box is a shallow cup-shaped member comprising a plate 4 having a central aperture 5 for communication with the tube 1, and an annular peripheral flange 6 which meets the plate in a gradual curve or arc of a circle instead of at right angles. The aperture 5 is surrounded by a neck or collar 7 which is adapted to enter into the elbow of the tube 1. 95 The plate 4 adjacent said neck is slotted as at 8 to receive the tongues 3 of the tube. In assembling the body-member and tube, the neck 7 is received in telescopic relation within the end of the tube 1 and the tongues 90 3 are received within the slots 8 and bent over into clamping relation with said body-member, as clearly shown in Fig. 2. 100

A diaphragm 9 of any suitable material such as mica, glass, paper, etc., is shown as 105 mounted within the cavity of the body-mem-

ber provided by the peripheral flange 6, preferably between a pair of gaskets 10 of any suitable material such as rubber, cork, paper, etc. To retain the diaphragm in position, a cover-like clamping ring 11 is provided. This ring is provided with a stamped up peripheral flange 12 which is telescoped over the flange 6 of the body-member 4 to cover the otherwise exposed outer edge of the outer gasket 10 and is also provided with a plurality of fingers 13, preferably equally and comparatively widely spaced around the same, of sufficient length to enable the same to be curved over onto the plate 4 of the body-member. In assembling the diaphragm and body-member, the diaphragm with its gaskets is inserted in place within the cavity of said body-member; the retaining ring is received over the flange 6 of said body-member and the fingers 13 are thereafter curved down from the dotted line position to full line position shown in Fig. 2 so as to clamp the diaphragm, gaskets and retaining ring firmly in position. Owing to the curvature between the plate 4 and flange 6, the fingers 13 are not bent down at a sharp right angle on to said plate but are curved into intimate contact with said plate and flange. This results in a spring-like grip of said fingers on the body member whereby a substantially uniform tension on the diaphragm is obtained as will now be readily understood.

Owing to the greater density of the drawn and stamped sheet-metal which the present invention renders available, a sound-box constructed in accordance with this invention is far lighter than those heretofore invented without the sacrifice of strength or other desirable properties. Furthermore, as the fingers 13 are bent into clamping position independently and so as to exert a uniform tension on the diaphragm, the latter will be supported without local stresses, as variations in the diaphragm, gaskets and clamping surfaces will be compensated for by the independent and uniform tension applied at a plurality of spaced points around the diaphragm-retaining ring. Additionally, a sound-box is thus provided which is equally satisfactory in reproducing as well as recording sound and one which can be manufactured easily and inexpensively owing to the simplicity of its component elements and facility with which they may be formed from sheet-material.

While the illustrated embodiment of the invention has been described with considerable particularity, it is to be expressly understood that the invention is not to be restricted thereto as the same is capable of receiving a variety of mechanical expressions

some of which will readily suggest themselves to those skilled in the art, while certain features thereof are capable of use without other features thereof. Reference is 65 therefore to be had to the claims hereto appended for a definition of the limits of the invention.

What is claimed is:—

1. A sound-box comprising an apertured 70 body-member of sheet-metal provided with slots adjacent said aperture, and a tube of sheet-metal provided with tongues received in said slots and bent over to clamp said body-member. 75

2. A sound-box comprising an apertured body-member of sheet-metal provided with a collar around said aperture and slots adjacent said collar, and a tube of sheet-metal in telescopic relation to said collar and provided with tongues received in said slots and bent over to clamp said body-member. 80

3. A sound-box having a body member consisting of a plate and an annular flange meeting the plate in a curve, a diaphragm in 85 spaced relation to said plate, and means for securing the diaphragm in position comprising a cover-like ring having a plurality of fingers curved over into intimate contact with the curved meeting part aforesaid. 90

4. A sound-box comprising a body-member, a diaphragm, and a diaphragm-retaining ring provided with a plurality of fingers curved over said body-member.

5. A sound-box comprising a body-member, a diaphragm, and a flanged diaphragm-retaining ring provided with a plurality of fingers curved over said body-member. 95

6. In a sound box, the combination of a diaphragm carrier having an aperture for 100 the passage of sound vibrations, a sound-conveying conduit having a wall in contact with said carrier, said conduit being closed at one end but having an aperture in its carrier-contiguous wall, and means for securing 105 the conduit to the carrier with the apertures in alignment comprising tongue - and - slot connections adjacent said apertures.

7. In a sound-box, a flanged body portion, and a diaphragm retaining-ring provided 110 with a plurality of integral and spaced tongues clampingly engaged about the body portion.

8. In a sound-box for sound recording and reproducing machines, a casing, and a diaphragm retaining-ring attached thereto by means integral with itself, said means being flanged over the edge of the casing inwardly from its periphery. 115

In testimony whereof I have signed this 120 specification.

JOHN J. SCULLY.
